US00D943673S

(12) **United States Design Patent** (10) Patent No.: **US D943,673 S**
(45) Date of Patent: **** Feb. 15, 2022**

(54) **DIGITAL SIGNAGE**

- (71) Applicant: **LG ELECTRONICS INC.**, Seoul (KR)
- (72) Inventors: **Hyunhee You**, Seoul (KR); **Yoonkyeong Lee**, Seoul (KR); **Yongho Lee**, Seoul (KR); **Jaewon Lim**, Seoul (KR)
- (73) Assignee: **LG ELECTRONICS INC.**, Seoul (KR)
- (**) Term: **15 Years**
- (21) Appl. No.: **35/510,551**
- (22) Filed: **Apr. 10, 2020**

(80) **Hague Agreement Data**

- Int. Filing Date: **Apr. 10, 2020**
Int. Reg. No.: **DM/207595**
Int. Reg. Date: **Apr. 10, 2020**
Int. Reg. Pub. Date: **Oct. 16, 2020**

(30) **Foreign Application Priority Data**

- Oct. 24, 2019 (KR) 30-2019-0050488
- (51) **LOC (13) Cl.** **20-03**
- (52) **U.S. Cl.**
USPC **D20/39**
